UNITED STATES PATENT OFFICE

CHARLES FISHER, OF YONKERS, NEW YORK, ASSIGNOR TO THE AUTOMATIC RECORDING SAFE COMPANY, OF CHICAGO, ILLINOIS, A CORPORATION OF ILLINOIS

SAVINGS BANK

Application filed February 23, 1929. Serial No. 342,121.

This invention relates particularly to savings banks, and the primary object is to provide a simple and improved device of this character simulating the appearance of a barrel.

The invention is illustrated in a preferred embodiment in the accompanying drawings, in which—

Fig. 1 is a perspective view of a savings bank embodying the invention; Fig. 2, a section taken as indicated at line 2 of Fig. 1; Fig. 3, a broken detail view; Fig. 4, an outer face view of a lock-equipment closure employed; Fig. 5, an inner face view of the same; Fig. 6, a view of the inner plate and attendant parts of said closure; Fig. 7, a reverse view of the lock-slide, or bolt, shown in Fig. 6; Fig. 8, a view similar to Fig. 6, but showing certain parts removed; Fig. 9, a view of the under one of a pair of fillets which are present in Fig. 8; Fig. 10, a broken sectional view taken at the plane indicated at line 10 of Fig. 4; Fig. 11, a broken section taken as indicated at line 11 of Fig. 10; Fig. 12, a fragmentary view corresponding with the view shown in Fig. 10, but showing the bolt of the lock retracted; and Fig. 13, a broken inner view showing a portion of one of the two semi-cylindrical casing-members employed, the dotted lines indicating the position of a longitudinal pin which serves to connect interior lugs with which the casing-sections are provided.

In the construction illustrated, A designates a body of general cylindrical form, simulating the appearance of the circumferential wall of a keg, or barrel, and comprising two semi-cylindrical sections A' and A'; B, a permanent closure with which the barrel is equipped at one end; and C, a removable closure which is equipped with a locking device, and, preferably, with a coin-slot and slot-guard device.

The casing-sections A' and A' preferably are molded or pressed from a suitable molding compound, as, for example, from a bakelite molding compound. Sections are complementary, each section being of concavo-convex form and preferably having a swell, so as to better simulate a barrel whose ends

are smaller than its central portion. Each of the sections of the casing A is provided internally at one end with a semi-annular flange 1 having small notches 1^a at the ends of the flange; and each section preferably is provided internally at the other end with a semi-annular groove 2. Each section is also provided near its edges with internal coupling lugs 3, 4 and 5. These lugs are formed integrally with the casing-section in the molding operation, and are provided with perforations adapted to receive longitudinal rods, or keys, 6 which serve to couple the sections together. The lugs of the two sections are complementary and come together in pairs; and the perforations through the lugs, or eyes, are properly positioned to draw the edge surfaces 7 of the sections tightly together. The perforations are in alignment with the notches 1^a of the flange 1, thus permitting the pins, or rods, 6 to be entered and forced into the eyes.

The central lugs 4 preferably have formed integrally therewith fillets having inclined surfaces 4^a, so that coins dropped in through the slot-enclosure C will slide over the central lugs so as to fill the lower portion of the keg.

In the molding operation, each section is provided with external longitudinal small grooves 8 and with semi-circular ribs 9 which extend across the grooves, so that the barrel has the appearance of being composed of staves and hoops, or bands.

The permanent closure B is shown as consisting of a metal disk, which may be of brass, the edge-portion of the disk being held in the groove 2. The exterior surface of the disk may be suitably enamelled and decorated, if desired. It may, if desired, contain the name of the savings bank institution which issues the small savings banks to depositors.

The closure C, in the illustration given, comprises an outer metal disk 10 which is provided with a coin-slot 10^a; and an inner metal disk 11 which is provided with a coin slot 11^a.

The inner disk 11 has its peripheral portion struck outwardly (toward the disk 10)

to provide a spacing-flange 11^b. At one point, this flange is interrupted and the metal extended to provide a fixed catch, or hook, 11^c, the intermediate portion of which is bent, as indicated at 11^a. At one wall of the slot 11^a, the metal is cut to provide bent projections 11^e and intervening fixed tongues 11^f, forming a portion of the slot-guard means.

10 The slot-guard device is completed by means of a resilient thin spring-metal member 12 which is bent into U-form and secured to the member 11 by means of a clenching-lug 11^g. The U-shape member 12 is provided with a pair of resilient tongues 12^a which normally lie against the plate 10 and whose extremities extend through the spaces between the lugs 11^c and across the coin-slot 10^a, as appears from Fig. 10.

20 At one side of the slot 11^a, the metal is shirred and bent to form a flange 11^b. The flange 11^b is cut away at the points 11^f, these points being opposite the catch-projections 11^c. A pair of fillet-plates 13 and 14, provided, respectively, with recesses 13^a and 14^a are mounted in the disk 11. The fillet-plates are provided with projections which engage the recesses 11^f. These fillet-plates also engage pins 20^a. A sliding U-shape bolt-plate 16 is interposed between disk 11 and the fillet-plates, and has projections 16^a which work through the slots, or recesses, 11^f. The bolt 16 has a flange 16^b, and a curved leaf-spring 17 is interposed between this flange and the flange 11^b.

30 The key-barrel 18 is journalled in the plates 10 and 11, this key-barrel extending through the recesses in the fillets and through the space between the furcations 16^a of the bolt. 40 The key 19 serves to actuate the lock. The recesses 13^a and 14^a serve to accommodate projections with which the key is provided. One of the projections 19^a of the key is adapted to engage the bottom of the recess in the bolt-plate 16 and retract the bolt against the pressure of the spring 17.

45 The plates, or disks, 10 and 11 are provided with perforations 20 which receive rivets 20^a, serving to connect the disks.

50 The lock-equipped closure C may be inserted so that it will rest on the flange 1 of the barrel-like casing of the savings bank, the hooks, or catches, 11^c being caused to engage beneath the flange and the furcations of the bolt 16 also being caused to engage beneath the flange 1.

55 The improved savings bank may be manufactured cheaply, and is extremely durable. The disks 10 and 11 and the lock-parts may be of brass, or other non-corrodible metal; and where a suitable molding compound is employed for forming the segments of the barrel, the savings bank, as a whole, is free from danger of rusting or corroding.

60 The foregoing detailed description has

been given for clearness of understanding only, and no unnecessary limitations should be understood therefrom, but the appended claims should be construed as broadly as permissible, in view of the prior art.

70 What I regard as new, and desire to secure by Letters Patent, is:

75 1. A savings bank closure comprising an outer plate provided with a coin-slot; an inner plate having an upturned peripheral flange abutting against the outer plate and spacing said plates, said inner plate being provided with a coin-slot and with upturned lugs adjacent thereto; means connecting said plates rigidly together; and a slot-guard comprising a U-shape plate having a shank secured to said inner plate and having resilient arms adjacent the inner surface of the outer plate extending across the coin-slot of the outer plate and working in the spaces between said lugs.

80 2. A closure as specified in claim 1, in which the inner plate is provided also with lugs projecting beyond said upturned lugs and disposed at a distance below the coin-slot of the outer plate.

85 3. A savings bank closure comprising an outer plate provided with a coin-slot; an inner substantially parallel plate spaced from the first-mentioned plate and provided with a coin-slot somewhat out of registration with said first-mentioned coin-slot; means securing said plates rigidly together; a slot-guard comprising a U-shape plate having a shank portion secured to said inner plate and having resilient arms extending across said first-mentioned coin-slot; and upwardly projecting lugs carried by said inner plate, said lugs being spaced to permit said resilient arms to work between them.

90 4. A closure as specified in claim 3, in which the inner plate is equipped also with lugs which project beyond said upwardly extending lugs and underlie the extremities of said resilient arms.

95 5. A closure comprising an outer plate; an inner plate spaced therefrom and rigidly secured thereto, said inner plate being equipped near one edge with a bolt guide and a flange back of said guide; a lock confined between said plates comprising a plate-like bolt having its rear end equipped with an unturned flange, a leaf spring interposed between said flanges, fillets interposed between said bolt and the outer plate, and a key-barrel journaled in the outer and inner plates and extending through said fillets and bolt.

100 6. A closure as specified in claim 5, in which the flange back of the guide constitutes a wall of a coin-slot through the closure.

105 CHARLES FISHER.
